UNITED STATES PATENT OFFICE.

JOHN McMULLEN, OF BUFFALO, NEW YORK.

CAR-UNCOUPLING DEVICE.

Application filed October 24, 1921. Serial No. 510,064.

The invention relates to uncoupling devices for railway cars and has for its objects to provide an uncoupling device composed of few parts, which is economical to manufacture, durable and accurate in operation.

A further object of the invention is to provide a device of the character described in which any tendency of the coupling pin to tilt or swing while being withdrawn from its seat is or may be accommodated by a compensatory movement of the lifting link.

With such objects in view as well as other advantages which may be incident to the use of the improvements, the invention consists in the parts and combinations thereof hereinafter set forth and claimed, with the understanding that the elements constituting the same may be varied in proportions and arrangement without departing from the nature and scope of the invention as hereinafter claimed.

In order to make the invention more clearly understood there are shown in the accompanying drawings means for carrying the same into practical effect, without limiting the improvements, in their useful applications, to the particular constructions which, for the purpose of explanation, have been made the subject of illustration.

In said drawings:—

Figure 1 is a side elevation of the uncoupling device in its preferred form as attached to the end sill of a car.

Fig. 2 is a plan view of the same.

Figs. 3 to 11 are detail views of the various component parts of the invention, further described in detail.

Referring to the drawings, 1 indicates the end sill of a freight car, 2 the draw bar provided with the usual draw head 3, and 4 the coupling pin, mounted in the usual manner for vertical reciprocation within the draw head. Suitably secured as by bolts 5 to the lower flange of the end sill and on the under side thereof is an ear member 6 having a depending U-shaped portion 7 within which is pivotally mounted at 21 intermediate its ends an uncoupling or lifting lever 8, preferably of metal and formed at its inner end with an eye or recess 9. Suitably secured as by bolts 10 to the end sill near its end and on the under side thereof is an ear member 11 which is bent upon itself to provide a pair of de-

pending lugs 12 between which is pivotally mounted at 20 a bell crank or hand operating lever 13 having its upper arm 14 offset and provided with a guide way or slot 15 through which the outer end of the lifting lever 8 is adapted to extend. It will be observed that the upper arm 14 of the operating lever forms a pedal which by being depressed serves to effect an uncoupling operation of the lifting lever 8. The pedal portion of the lever, which is preferably flat, conveniently enables the trainman to operate the device while riding upon the car by pressing downwardly thereon with his foot.

16 is a pin engaging and lifting link provided near its inner end with an off-set portion 17 which insures the pivotal engagement of its inner end with the eye or recess 9, the lower end of said portion 17 being riveted over so it will not become disengaged from said recess 9 of the lever 8, thus permitting the link to swing freely in a horizontal plane and preventing its extending more than a predetermined distance through the recess. The link 16 is further provided with a second off-set portion 18 which gives to the link the necessary elevation for it to extend horizontally through and operatively engage the eye of the coupling pin 4. The inner end of the link is upturned as at 19 to insure the continued engagement of the link with the coupling pin.

By the above described construction it will be seen that the pivotal mounting of the link 16 insures its proper engagement with the coupling pin when the device is operated, and any tendency of the pin to tilt while being withdrawn from its seat is immediately compensated for by the swinging of the link in a horizontal plane to accommodate any lateral tilting on the part of the coupling pin and the possibility of the link or coupling pin binding or sticking during the operation of the device is thereby effectually prevented.

The operation of the device is as follows: When it is desired to lift the coupling pin to couple or uncouple cars the operator either may pull outwardly on the bell crank lever 13 which is conveniently located near the side of the car or he may press downwardly on the pedal 14. The slotted arm 14 of the bell crank swings downwardly in a vertical plane parallel with the end sill

and carries with it the outer end of the pivoted lever 8. The inner end of said lever swings upwardly, raising the link 16 and lifting the coupling pin 4 from its seat, 5 the link 16 being free to swing horizontally in the recess 9 to accommodate any lateral movement of the pin 4. By releasing the hand lever 13 the pin drops back by gravity 10 into its seat in the draw head 3 and the parts are returned to normal position as shown in Fig. 1.

What is claimed is—

1. An uncoupling device for railway cars, comprising in combination: an end sill, a draw bar mounted near said end sill and having a draw head and coupling pin, a lifting lever pivotally mounted on said end sill, a pin engaging and lifting link pivotally mounted at one end on said lever 20 and permanently engaging said lever against displacement, and operatively engaging at its other end said coupling pin to lift same, and a hand lever pivotally mounted on said end sill and having a slotted 25 portion and a pedal portion cooperatively engaging the outer end of said lifting lever to raise the inner end of said lifting lever, whereby said coupling pin is lifted from said draw head.
2. An uncoupling device for railway cars comprising in combination with the locking pin of a car coupler, a lever pivotally mounted between its ends, and a pivoted member adapted to actuate said lever, 35 said pivoted member having a handle portion projecting downwardly from the pivotal axis of said member and being provided with a pedal extending inwardly from the said pivotal axis towards the car coupler, said member being adapted to be actuated by pressure applied either to said handle or to said pedal.
3. An uncoupling device for railway cars, comprising in combination: an end sill, a 40 draw bar near said end sill and having a draw head and coupling pin, a hand oper-

ated bell crank lever pivotally mounted on said end sill and adapted to swing in a vertical plane substantially parallel with said end sill, said bell crank lever having a flattened portion, a depending slotted arm, a lever pivotally mounted intermediate its ends on said end sill and adapted to swing in a vertical plane substantially parallel with said end sill and having one end operatively engaged by the slot in said bell crank lever and carrying at its other end an eye portion, and a link having at one end an offset portion supported in and operatively engaged by said eye portion of said lever and at its other end operatively engaging said coupling pin to lift the same.

4. An uncoupling device for railway cars and the like, comprising in combination with the locking pin of the car coupler; a 50 pivotally mounted lifting lever; a lifting arm mounted on the inner end of said lifting lever and having a sliding engagement with the uncoupling pin; a hand operated bell crank lever having one arm fashioned with a pedal and adapted to be operatively connected with the outer end of said lifting lever by a slotted connection and having its other arm normally depending at right angles to said lifting lever.

5. An uncoupling device for railway cars and the like, comprising in combination with the locking pin of the car coupler, a pivotally mounted lifting lever; a lifting arm mounted on the inner end of said 55 lifting lever and having a sliding engagement with the uncoupling pin, a hand operated bell crank lever having one arm formed with a pedal extending over and adapted to engage the outer end of said lifting lever and having its other arm depending substantially perpendicularly to the outer end of said lifting lever.

In testimony whereof I have set my hand to the foregoing specification.

JOHN McMULLEN.
